Primary Examiner — Clint A Samuel(74) *Attorney, Agent, or Firm* — Rivka Friedman(57) **CLAIM**

The ornamental design for a lamp, as shown and described.

DESCRIPTION

FIG. 1 is a perspective view of a lamp showing my new design.

FIG. 2 is a right side view thereof;

FIG. 3 is a left side view thereof;

FIG. 4 is a front view thereof;

FIG. 5 is a top view thereof;

FIG. 6 is bottom view thereof;

FIG. 7 is an exploded view thereof; and,

FIG. 8 is a lateral view thereof together with a bench.

The broken lines in the Figures show portions of the lamp which form no part of the claimed design.

1 Claim, 8 Drawing Sheets(56)
